UNITED STATES PATENT OFFICE.

JESSE L. BOYNTON, OF NEW YORK, N. Y., ASSIGNOR OF FIFTY PER CENT TO CHARLES A. MARSHALL, OF NEW YORK, N. Y.

METHOD AND APPARATUS FOR TIMING THE USE OF ELECTRICAL CIRCUITS.

Application filed May 31, 1927. Serial No. 195,394.

- This invention relates to methods and apparatus for timing or approximately timing the use of electrical circuits and one example of the invention as hereinafter described is particularly adaptable for controlling overtime payments for numerous telephone calls, however the invention in its broader aspects may be employed in connection with various other electrical systems and circuits.
- 10 The invention includes among its objects the provision of a suitable method and apparatus of the class above indicated, which will be simple, effective and dependable in operation and which will neither embody expensive equipment nor absorb any considerable portion of the time and energy of the operative.
- 15 Further and more specific objects, features and advantages will more clearly appear from the detailed description given below taken in connection with the accompanying drawings which form a part of this specification.
- 20 In the drawings, Fig. 1 is a perspective view showing a part of the equipment at an operator's position at a telephone central office switchboard such as adapted for the control of numerous telephone calls.
- 25 Fig. 2 is a schematic diagram showing the electrical circuit connections for a plurality of signal lamps which may be used according to this invention at several operators' positions.
- 30 Fig. 3 is an elevational view partly in section showing a sleeve member as one form of electrical circuit marking means, applied to a register key of a switchboard as of Fig. 1.
- 35 The invention is here described, by way of example, in the form according to which it may be used for numerous telephone lines connected to prepayment telephones such as coin box telephones as now widely used in public telephone booths. In order to give economical and efficient service for such telephones, a number, usually as many as 40 or more, of such telephone lines are arranged to be under the control of each central station operator. The operator is thereby kept substantially continuously at work in the making of connections and has little or no opportunity to give attention to the timing of individual calls. Furthermore, it will be appreciated that any dependable apparatus which might be applied individually to each such line to automatically time the calls thereon, would necessarily be comparatively expensive to manufacture and install.
- 45 On the other hand, according to the method of my invention, provision is made at regular predetermined intervals for periodically indicating and checking at one time all calls which have continued substantially beyond a payment period. To this end I provide a suitable signal at each operator's position for giving an indication to the operator at regular predetermined intervals of time, which intervals may for example be equal to an established payment period such as five minutes. Such signal may be of visual, audible or other type and should preferably be sufficiently pronounced or so positioned as to effectively attract the operator's attention even though the operator is very actively engaged in observing other signals and making connections. This signal indication given at accurately measured arbitrary but regular intervals calls the operator's attention to the fact that at that time certain steps must be taken in regard to overtime calls. According to the preferred method of practicing my invention, the operator is provided with numerous marking means intended to be applied, whenever such signal indication is given, to all prepayment or other lines over which calls are being made at that time. Such marking means may take the form of cylindrical sleeves each of which may be placed over a register key or other control device identified with a particular line for indicating that a call is being carried by such line at the time the signal indication is given.
- 55 All of the lines carrying calls may thus be quickly marked by the operator with sleeves, and then the operator is free to proceed with the usual duties until the next predetermined signal indication is given. Meanwhile as the calls on the various lines thus marked are terminated, the marking is effaced. That is, the sleeves may be removed and the calls registered or collections made therefor as terminated, in the ordinary way. However, if any of such marked calls are continued until the next signal indication is given, the lines therefor will be identified by the marking sleeves which have not yet been removed. For such calls as these which

have extended at least beyond the established payment period, the operator may then demand or make suitable records for additional payments before permitting the calls to continue. At the same time the operator will observe the lines carrying calls which are not identified by marking sleeves and will thereupon apply marking sleeves to the register keys of such lines. Likewise, 10 during each following measured interval and at each succeeding signal indication, the operator takes similar steps to check and control overtime payments for all of the numerous lines.

15 Referring now to the drawings wherein apparatus is indicated for carrying out my invention according to the particular manner above outlined, in Fig. 1 a panel of a section of a telephone central station switchboard is indicated at 10. It will be understood that several of such panels may be mounted at an operator's position to be controlled by a single operator, or at times by adjacent operators. It will also be understood 20 that numerous operators' positions will usually be located side-by-side along a switchboard in the conventional manner, a single position being here shown merely for the sake of simplicity.

25 30 A group of "subscribers' multiple" jacks is indicated at 11. A group of "out trunk multiple" jacks is indicated at 12. An "answering jack" for each of the coin box or other telephone lines is provided in the 35 group indicated at 13. A row of "back cords and plugs" is indicated at 14, such plugs being adapted to plug into the "answering jacks" when a phone user signals in the conventional manner to make a call. A 40 row of "front cords and plugs" is indicated at 15, such plugs being adapted to plug into the "subscribers' multiple" jacks or the "out trunk multiple" jacks, depending upon the destination of the call to be made. A group 45 of line supervisory lamp signals of conventional form is indicated at 16; a row of "register" or "collect" keys is indicated at 17, each of such keys being designed to register a call when terminated and before the operator 50 takes down the corresponding connection cords. "Listening-in keys" and "ringing keys" are indicated respectively at 18 and 19. The parts of this apparatus thus far noted 55 may all be of the conventional type found in modern central office equipments.

60 The visual indicating signal above referred to is here shown in the form of a signal lamp 20 located at the lower portion of the section 10. This signal lamp may be 65 generally similar in construction to the conventional type of sectional pilot lamps as indicated at 21 and 22. The circuit connections of the lamp 20 may be controlled by a suitable timing device, one form of which is hereinafter described. Such device is ar-

ranged to cause the light to flash at each pre-determined regular interval of, for example, 5 minutes.

The marking sleeves for identifying the lines over which calls are being made are 70 shown at 23 and 24, such sleeves here being applied to the first and third register keys which correspond to the first and third pair of plug and cord connections which are here shown as being in use. A group of extra 75 sleeves ready for the operator's use is indicated at 25.

In the apparatus as above described, it will be observed that while the calls are checked every 5 minutes, it will often be possible for a user to continue a call for a period somewhat longer than 5 minutes. For example, if connections are made over a line just after a signal indication, the user would be permitted to continue his call throughout that interval, which would continue for 4 and a fraction minutes and he would also be able to continue throughout the succeeding 5 minute interval, thus permitting him to use the line for a total period of 9 and a fraction minutes. But in actual practice, if each user continued his call until additional payment were demanded, the highest average length of call would be approximately 90 7½ minutes. However, since many of the users will not continue their call until notified of the expiration of their time, the average overtime call will be discontinued or will be checked within a time considerably under 95 7½ minutes. This method will therefore be 100 quite ample to eliminate the practice of individuals who persistently continue their calls substantially beyond the established payment period. The accomplishment of this purpose is highly advantageous, particularly with coin box telephones located where space is valuable and where in order to justify the proprietor of the store or other establishment in installing a phone booth, revenue must be continuously collected 110 throughout the day. Without such overtime prepayment control, it is of course possible for individuals to continue a call for a long period of time, thus often holding a valuable trunk line in use, necessitating additional trunk line investments as well as keeping other individuals from using the booth for indefinite periods. Without such systematic control of the timing, it is impossible for the central station operator to 115 proceed with the regular duties of making line connections and at the same time watch individually a multiplicity of calls. Accordingly, with payment telephones as now widely used, the users are usually free to 120 continue local calls indefinitely. Central offices operating in accordance with my invention may collect a substantial amount of overtime revenue, but only from deliberate 125 overtime use and the collection of such addi-

130

tional revenue is accomplished substantially without expense or danger of error and trouble beyond the usual operation of the central station switchboard. The operator's 5 attention and activities are diverted to the overtime payment matter only when additional payments are actually collected, or when a call is to be terminated.

If it is desired to reduce the highest average 10 overtime call period to a time less than $7\frac{1}{2}$ minutes (assuming that the established payment period is 5 minutes), an additional signal may be installed to give indications alternately with the first signal, that is, at 15 times half way between the indications of the first signal, so that all calls may be checked at regular predetermined intervals of $2\frac{1}{2}$ minutes. To avoid confusion, the two signals should have distinguishing characteristics. For example, the first signal may be a red lamp and the second a green lamp. Corresponding distinguishable red and green sleeves may be provided. Such a second or green signal lamp is indicated at 26 20 on the drawings. Each time that the red lamp indication is given the operator marks all register keys of calls then being made, with red sleeves. Then, when the green signal indication is given, calls not marked 25 with such red sleeves are marked with the green sleeves. Thereafter whenever a red signal indication is given, additional payment is demanded on all lines marked with red sleeves, and likewise when succeeding 30 green signals are given, additional payments are demanded on lines marked with green sleeves, until such time as the marked calls are discontinued. With this arrangement the highest average overtime call is reduced 35 to $6\frac{1}{4}$ minutes. It will be understood that a further plurality of distinguishable signals 40 to be accompanied by corresponding distinguishable markers might be used to further reduce the average period to a time more closely approaching the actual established 45 payment period. However, for most practical conditions one or two signal lamps will accomplish the desired results without substantially adding to the operator's work.

With numerous operators' positions side-by-side, it is desirable that adjacent operators should not be simultaneously engaged in 50 checking and registering numerous calls. Accordingly, it is desirable to have the respective predetermined signal indications 55 for a series of operators' positions given successively in rotation. Suitable circuit connections providing for such operation of the signal lamps is indicated in Fig. 2, wherein 60 signal lamps 20, 26, 20', 26', 20'' and 26'' are shown for three adjacent operators' positions. A rotatable contacting switch is indicated at 27 operated by clockworks to make one complete revolution during each established 65 payment period of, for example, 5

minutes. Around the circumference of this switch a series of contacts is provided, one for each of the several signal lamps to be controlled. These contacts may be individually connected to their corresponding signal lamps and are designed to successively make contact with the rotatable contact arm 28 which in turn is connected to a source of power 29, the opposite terminal of which is connected to all of the signal lamps. With 70 this arrangement, if an operator is engaged in collecting an overtime payment, the adjacent operators, who will perform, not be thus engaged at the time, will be free to assist in promptly attending to any new calls. 75

It will thus be observed that a practical method and apparatus is provided which will be highly economical and efficient, and even though a very small amount of the operator's time is taken in controlling numerous calls, the possibility of errors and confusion is minimized.

It is not desired to limit the invention to the details or specific examples herein described, since it will be apparent to those skilled in the art after understanding the invention, that it is susceptible to various other adaptations and modifications, such as may be made without departing from the scope of the invention, and I aim therefore 90 in the appended claims to cover all such adaptations and modifications. For example, various forms of line marking or identifying means other than the sleeves will readily suggest themselves, or if desired, groups 95 of lines in use for various periods of time may be classified for identification merely by arranging or using the connection devices in groups, such groups being used alternately or in rotation, and each group being identified with a corresponding distinguishable signal indicator.

What I claim as new and desire to secure by Letters Patent of the United States is:

1. Means for approximately timing and controlling over-time payments for numerous pre-payment telephone calls, the lines for which are under the control of a central office operator, comprising a signal common to numerous lines for giving an indication to the operator at regular intervals of time equal to an established payment period, in combination with marking means effaceable upon termination of calls for individually marking lines carrying calls at the times of said indications, whereby upon the next signal indication the operator is apprised of such calls as have extended beyond the established payment period and may then demand additional payments before permitting such calls to continue.

2. Means for approximately timing and controlling over-time payments for numerous payment telephone calls, the lines for which are under the control of a central 130

- office operator, comprising a distinctive signal common to numerous lines for giving an indication to the operator at regular intervals of time equal to an established payment period, another such signal but distinguishable from the first for giving indications alternately with the indications of the first mentioned signal, and marking means effaceable upon termination of calls 5 for individually marking lines carrying calls at the times of said indications, the marking means corresponding to one signal being distinguishable from the marking means corresponding to the other signal, whereby the 10 operator twice for each payment period is apprised by said indications of such calls as have extended beyond one established payment period.
3. Timing means for controlling over-time payments for numerous payment telephone calls, the lines for which are under the control of a central office operator, comprising a plurality of distinctive signals each for successively giving distinctive indications to 15 the operator at regular predetermined intervals of time, the periods for the respective signals overlapping but being of uniform duration equal to an established payment period, in combination with a plurality of types of distinctive marking means effaceable upon termination of calls for individually marking lines carrying calls and not previously marked at the times of said indications, the type of marking means applied upon the occurrence of a particular distinctive type of indication having corresponding distinctive characteristics.
4. Means for approximately timing the use of numerous electrical circuits, the connections for which are under the control of an operator, comprising a signal for giving an indication to the operator at regular predetermined intervals of time, in combination with effaceable marking means for individually marking circuits in use at the times of said indications, whereby upon the next signal indication the operator is apprised of such circuits as used beyond one predetermined period.
5. Timing means for controlling the use of numerous electrical circuits, connections for which are under the control of an operator, comprising a plurality of different distinctive signals each for successively giving distinctive indications to the operator at regular predetermined intervals of time, the periods for the respective signals overlapping but being of uniform duration equal to an established limited period of use, in combination with a plurality of types of distinctive marking means effaceable upon termination of the use of a circuit for individually marking circuits in use at the times of said indications, the type of marking means applied upon the occurrence of 20 a particular distinctive type of indication having distinctive characteristics identified with such type of indication.
6. Means for approximately timing and controlling over-time payments for numerous payment telephone calls, the lines for which are under the control of a central office operator, comprising a signal lamp at the operator's position for giving a flash attracting the operator's attention at regular intervals of time equal to an established payment period, and marking sleeves for individually marking the register keys of lines carrying calls at the times of said indications, whereby upon the next signal flash 25 the operator is apprised of such calls as have extended beyond the established payment period and may then demand or make records for additional payments before permitting such calls to continue.
7. Means for approximately timing numerous payment telephone calls, the lines for which are under the control of an operator, comprising a signal for giving an indication to the operator at regular intervals of time bearing a predetermined relationship to an established payment period, and means for individually marking lines carrying calls at the times of said indications, whereby upon the succeeding signal indications the operator may be apprised of such calls as have extended over a period of payment.
8. Method of approximately timing the use of numerous electrical circuits the connections for which are irregularly set-up and are controlled by an operator, which comprises giving the operator signal indications at predetermined regular intervals, the operator marking individually the circuits in use at the occurrence of each indication and effacing such marking upon termination of the use of each circuit thus marked, or registering the continued use of such marked circuits as are still in use upon occurrence of the succeeding indication.
9. Method of controlling over-time payments for the use of numerous telephone circuits the connections for which are irregularly set-up and are controlled by an operator, which comprises giving the operator signal indications at predetermined regular intervals, the operator marking individually the circuits in use at the occurrence of each indication and upon the next indication demanding or making records for additional payments for continued use of circuits thus marked.
10. Method of approximately timing the use of numerous electrical circuits the connections for which are irregularly set-up and are controlled by an operator, which comprises giving the operator a plurality of different distinctive signal indications at predetermined regular intervals, the operator marking individually with corre-

sponding distinctive means the circuits in use at the occurrence of each such indication and effacing such marking upon termination of the use of each circuit thus marked, or registering the continued use of such distinctively marked circuits as are still in use upon reoccurrence of the corresponding distinctive indication.

11. Method of controlling over-time payments for numerous pre-payment telephone calls, the lines for which are under the control of a central office operator, which comprises giving the operator a pronounced visual signal indication at predetermined regular intervals of time equal to an established payment period, the operator marking individually the lines carrying calls at the times of said indications, and effacing such marking upon termination of calls, and upon reoccurrence of the signal indication demanding additional payments for any desired continued use of lines thus marked.

12. Method of controlling over-time payments for numerous payment telephone calls, the lines for which are under the control of a central office operator, which comprises giving the operator a pronounced visual signal indication at predetermined regular intervals of time bearing a definite relationship to an established payment period, the operator marking individually the lines carrying calls at the times of said indications, and effacing such marking upon termination of calls, and upon succeeding signal indications demanding additional payments for over-time use of lines thus marked.

13. Means for approximately timing the use of numerous electrical circuits, the connections for which are controlled from a switchboard having a series of side-by-side operators' positions, comprising signals at each operator's position for giving indications at regular predetermined intervals of time, in combination with numerous effaceable marking means for individually marking circuits in use at each position at the times of said indications for such position, whereby upon succeeding signal indications the operators are apprised of circuits which have been continued in use beyond one complete predetermined period or longer, and means to operate said signals successively in rotation at the respective successive operators' positions.

14. Method of controlling the times of use of numerous electrical circuits the connections for which are established at irregular intervals by an operator in response to subscriber's demands, which comprises providing signal indications at regular predetermined times to denote the beginning and ending of successive arbitrary intervals each bearing a predetermined relationship to an established period of use for such circuits,

the operator directing attention at each such indication to the control of all circuits in continuous use since the previous such indication.

15. Method of controlling over-time payments for the use of numerous telephone lines the connections for which are established at irregular intervals according to the subscribers' demands, which comprises identifying all lines in use at regular arbitrary predetermined intervals, such intervals being equal to an established payment period or to a predetermined fraction thereof, and charging an over-time payment or payments for the use of such identified lines for which connections are set up in one such period and are maintained to the end of the next succeeding period or longer.

16. Method of controlling and charging for the use of numerous telephone lines upon which calls are instituted and terminated at irregular intervals, which comprises arbitrarily dividing the elapsed time into regular intervals equal to an established payment period or to a predetermined fraction thereof, and identifying or classifying, and charging extra amounts for the use of lines for which connections are established in one such period and are maintained to the end of the next succeeding period or longer.

17. Means for approximately timing the use of numerous electrical circuits, the connections for which are controlled from a switchboard having a series of side-by-side operators' positions, comprising signals at each operator's position for giving indications at regular predetermined intervals of time, in combination with identifying means at each position showing which circuits are in use at the times of said indications for such position, whereby upon succeeding signal indications the operators are apprised of circuits which have been continued in use beyond one complete predetermined period or longer, and means to operate said signals successively in rotation at the respective successive operators' positions.

18. Method of controlling over-time payments for numerous payment telephone calls, the lines for which are under the control of a central office operator, which comprises giving the operator a pronounced visual signal indication at predetermined regular intervals of time bearing a definite relationship to an established payment period, the operator identifying the lines carrying calls at the times of said indications, and upon succeeding signal indications charging additional payments for further use of such identified lines.

19. Method of approximately timing the use of numerous electrical circuits the connections for which are irregularly set up and are controlled by an operator, which comprises giving the operator various distinc-

tive signal indications at predetermined regular intervals, the operator identifying in a distinctive manner the circuits in use at the occurrence of each such indication and charging for the continued use of such distinctively identified circuits as are still in use upon reoccurrence of the corresponding distinctive indication.

20. Method of approximately timing the use of numerous electrical circuits the connections for which are irregularly set up and are controlled by an operator, which comprises giving the operator alternately differ-

ent distinctive signal indications at predetermined regular intervals, the operator identifying in a distinctive manner the circuits in use respectively at the occurrence of each such different indication and charging for the continued use of such distinctively identified circuits as are still in use upon reoccurrence of the corresponding distinctive indication. 15 20

In testimony whereof I have signed my name to this specification.

JESSE L. BOYNTON.
